C. F. BURGESS,
BATTERY HAND LAMP.
APPLICATION FILED APR. 6, 1920.

1,403,538.

Patented Jan. 17, 1922.

UNITED STATES PATENT OFFICE.

CHARLES F. BURGESS, OF MADISON, WISCONSIN, ASSIGNOR TO BURGESS BATTERY COMPANY, OF MADISON, WISCONSIN, A CORPORATION OF WISCONSIN.

BATTERY HAND LAMP.

1,403,538.

Specification of Letters Patent. Patented Jan. 17, 1922.

Application filed April 6, 1920. Serial No. 371,599.

To all whom it may concern:

Be known that I, CHARLES F. BURGESS, a citizen of the United States, residing at Madison, in the county of Dane, State of 5 Wisconsin, have invented certain new and useful Improvements in Battery Hand Lamps; and I do hereby declare the following to be a full, clear, and exact description of the invention, such as will enable 10 others skilled in the art to which it appertains to make and use the same.

Battery hand lamps as ordinarily constructed throw a rather concentrated beam of light of relatively small diameter. For 15 some purposes, as for work at a desk or around machinery, a more diffused light is desirable.

It is one of the objects of the present invention to provide a battery hand lamp so 20 constructed that it easily can be converted for use in delivering diffused light, or the usual concentrated beam, as occasion may require.

To this end, the reflector for the lamp is 25 of special construction, and is removable with the lens and lens-supporting ring to leave an operative battery lamp, adapted, like the ordinary candle, for distributing light in substantially all directions.

30 It is a further object of the present invention to so mount the lamp and its associated parts that the lamp is protected against shock or impact from the battery, is readily accessible for adjustment or renewal, and is so mounted that ready access 35 can be had to the battery chamber, to the switch mechanism, and to all operative parts of the structure.

It is a further object of the present invention to permanently mount the lens and reflector in the lens-supporting ring or head so that on removal of the head all of 40 these parts come off together and can be re-installed without inconvenience or difficulty.

45 Further objects and advantages will become clear from the following detailed description, which is to be taken in conjunction with the accompanying drawings, wherein—

50 Fig. 1 is an elevation of a battery candle to

which a lens-supporting ring can be added if a concentrated beam of light is desired;

Fig. 2 is a sectional elevation through a complete hand lamp; and

Fig. 3 is a section on the line 3—3 of 55 Fig. 2.

In the embodiment illustrated in the drawing, the dry cells 1 and 2, of which any suitable number may be provided, are arranged end to end in series relation within 60 a paper tube 3. The naked bottom of the lowermost dry cell is electrically connected through a helical spring 4 with a metal bottom cap 5 screw-threaded to the lower end of the metal tube 6, which forms the casing 65 of the hand lamp.

At the front end of casing 6, and detachably connected therewith, as by means of radial pins 7 and bayonet slots 8, is a metal collar 9 with a flange 10 at its front edge. 70 In this collar is screwed or otherwise fastened a bumper block 11 of insulation, such as hard fiber, carrying in a central opening, and preferably screw-threaded thereto, a socket 12 for an incandescent lamp 13. 75 The upper edge of this socket may be flared outwardly to form a small reflecting surface. Beneath this socket is an enlarged cavity wherein is an S-shaped leaf spring 14, with which the upper or carbon electrode 15 of the topmost dry cell makes contact. A flanged metal thimble 16 serves as a guard to prevent the spring from dropping out of the cavity. The upper leaf of the spring makes contact with the inner 80 terminal 17 of the lamp. 85

Mounted on casing 6 is the usual thumb button 18 and sliding finger 19, the front resilient end of which can be brought into contact with a screw 20 connected by a wire 90 21 with lamp socket 12, as shown in Fig. 1.

The structure above described, which is illustrated in Fig. 1, constitutes what, for convenience, I prefer to designate as a battery candle. It is completely operative to 95 give diffused light and the lighting of the lamp from the battery is under full control of the switch mechanism and its actuating button 18.

In addition to the structure above de- 100

scribed, there may be and preferably is provided a detachable head, the details of which may vary, but one satisfactory embodiment of which is illustrated in Fig. 2. The flaring head 22 there shown has threaded engagement with the detachable collar 9 and carries reflector 23 and a lens 24. The lens may be convex or plain and seats on a flange 25 of the reflector. Head 22 is shaped 10 with a shoulder 26 on which this reflector flange seats and the upper edge of the head 22 is spun over to form a flange 27 by which the lens and reflector are permanently attached to the flaring head 22. The opening 15 at the center of the reflector is larger than the lamp bulb and preferably is larger than the upper flaring portion of the lamp socket 12, so that a small annular insulating air gap 28 intervenes between the reflector and 20 the lamp socket. The lens-supporting head is preferably smooth on its outside, except for the threads by which it may be attached to collar 9.

With the arrangement above described, 25 the usual concentrated beam of light is thrown by the hand lamp when the switch is closed at screw 20, and if a diffused light is desired, it is only necessary to unscrew the flaring head from the other parts to convert the hand lamp into the battery candle 30 shown in Fig. 1. This adjustment may be made even when the lamp is burning and without disturbing in any way the normal operative relation between the battery and the incandescent lamp. If but a slight alteration 35 in the character of the beam is desired, this may be effected by partially unscrewing the head, for by so doing the reflector shifts with respect to the lamp, and 40 the filament of the lamp moves with respect to the focii of the lens, and of the reflector, with resultant changes in the character of the beam delivered by the hand lamp.

45 The batteries can, of course, be renewed through the bottom end of the casing, but if for any reason access is desired through the front end of the battery casing, as, for instance, to force out dry cells that have become swollen and stuck, or for adjustment 50 or repair of the switch mechanism, etc., collar 9 can be rotated to free pins 7 in their bayonet slots, and thereupon collar 9, with all the parts carried thereby, can be withdrawn, and the top of the battery be exposed.

55 The facility with which the hand lamp can be taken apart and put together is of great convenience to the user, and particularly to salesman demonstrating the device, 60 for the reflector and the lens are always held in proper operative relation to the enlarged head, and the other adjustable parts are carried by ring 9. The bright surface of reflector 23 need not be touched by the 65 fingers and so keeps bright even though it

may have a delicate and highly polished face.

Other objects and advantages of the construction described will be apparent to those skilled in this art, and changes in details of the several parts are contemplated within the scope of the invention, as defined by the appended claims.

I claim:

1. A battery hand lamp having a lamp 75 and an enlarged outwardly flaring metal head with a lens and reflector attached thereto and removable therewith from the hand lamp, said lens and reflector both being permanently held between a flange and shoulder of said flaring metal head and being movable therewith when the distribution of the beam of light is to be altered, said reflector having an opening through which the bulb of said lamp will pass.

80 2. A battery hand lamp having a lamp and a casing and having an enlarged outwardly flaring metal head threaded to said casing, a lens and a reflector in said head and removable therewith from the hand lamp, said lens and reflector both being permanently held between a flange and shoulder at the front edge of said flaring metal head, and being movable therewith to change the distribution of the beam of light when said head is turned on the threads of said casing, said reflector having an opening through which the bulb of said lamp will pass, substantially as described.

85 3. In a battery hand lamp, the combination of a battery, a casing therefor, an insulating disc closing the end of said casing and secured thereto to take the thrust of the battery, a lamp carried by said disc and protruding beyond the end of said casing and in 90 operative relation to said battery to form a complete battery candle, a reflector for said lamp, and a flaring metal head supporting said reflector and movable therewith when the distribution of the beam of light is to be 95 altered.

100 4. In a battery hand lamp, the combination of a lamp, a casing, a metal head threaded to the front end of said casing, a reflector held in position by said metal head 105 and having an opening through which said lamp will pass, a battery in said casing, means supporting said lamp and taking the thrust of the front end of the battery, and a spring completing the electrical connection 110 from said battery to the inner terminal of said lamp.

115 5. In a battery hand lamp, the combination of a casing, a battery of dry cells therein, a lamp connected with one terminal of 120 said battery, a socket in which said lamp is threaded, a rigid insulating support for said socket, said support being secured in said casing to take the forward thrust of the battery, a reflector insulated from said socket 125

and spaced therefrom and movable with respect thereto to focus the light, and means for establishing a switch-controlled electrical connection from the other terminal of 5 said battery to said socket.

6. In a battery hand lamp, the combination of a battery, a lamp in operative relation thereto, a casing for said battery, an insulating disc attached to and closing the end 10 of said casing and whereby said lamp is supported, and a reflector for said lamp removable therefrom without disturbing the operative relation of said lamp to said battery, substantially as described.

15 7. In a battery hand lamp, the combination of a battery, a casing therefor, a lamp, a socket for said lamp, an insulating disc closing the end of said casing and taking the forward thrust of the battery and supporting 20 said socket, a reflector insulated from said socket and having a central opening through which the lamp bulb will pass, and means for adjusting said reflector with relation to said socket to change the focus of 25 the beam of light.

8. In a battery hand lamp, the combination of a battery, a lamp in operative relation thereto, a socket for said lamp, a disc supporting said socket and taking the forward 30 thrust of the battery, a reflector insulated from said socket, and means for moving said reflector with respect to said socket when the distribution of light from said lamp is to be altered.

35 9. In a battery hand lamp the combination of a battery, a casing therefor, an insulating disc closing the end of said casing, a threaded socket in said insulating disc, a lamp in said socket in operative relation to

40 said battery to form a candle, an outwardly flaring metal head detachably secured to said casing, and a reflector carried at the outer edge of said flaring metal head and having an opening through which said lamp will 45 pass, said reflector being adapted to seat on said insulating disc when desired, substantially as described.

10. In a battery hand lamp the combination of a battery, a casing therefor, an insulating disc closing the end of said casing, a threaded socket carried by said insulating disc, a lamp in said socket in operative relation to said battery to form a candle, a metal head detachably secured to said casing, and 55 a reflector carried at the outer edge of said metal head and having an opening through which said lamp will pass, the edge of said opening being always separated from said socket by an insulating air gap and said reflector being adjustable with respect to said socket when the distribution of light from

said lamp is to be altered, substantially as described.

11. In a battery hand lamp the combination of a battery, a casing therefor, a rigid 65 insulating disc at the end of said casing, a threaded socket in said insulating disc, a lamp in said socket in operative relation to said battery to form a candle, an outwardly flaring metal head detachably secured to 70 said casing, and a reflector permanently secured at the outer edge of said flaring metal head and having an opening through which said lamp will pass, the edge of said opening being always separated from said 75 socket by an insulating air gap and said reflector being adjustable with respect to said socket when the distribution of light from said lamp is to be altered, substantially as described.

12. In a battery hand lamp the combination of a battery, a metal casing therefor, a collar detachably secured to the front end of said casing, a rigid insulating disc secured in said collar, a threaded socket in said insulating disc, a lamp in said socket in operative relation to said battery to form a complete and operative battery candle, an outwardly flaring metal head secured to said collar and removable therewith from said 90 casing, and a reflector carried at the outer edge of said flaring metal head and having an opening through which said lamp will pass, substantially as described.

13. In a battery hand lamp the combination of a metal case, a battery therein, a threaded metal collar detachably secured to the front end of said case, an insulating disc secured to said detachable collar, a threaded lamp socket secured in said disc, a 100 lens and a reflector, and a metal head at the front edge of which said lens and reflector are mounted and by which they may be adjusted with respect to said lamp, said reflector having an opening through which 105 said lamp will pass.

14. In a battery hand lamp the combination of a metal case, a battery therein, a threaded metal collar detachably secured to the front end of said case by a bayonet joint, 110 an insulated disc threaded to said detachable collar, a threaded lamp socket secured centrally in said disc, a lens and a reflector, and a flaring metal head at the front edge of which said lens and reflector are permanently mounted and by which they may be adjusted with respect to said lamp, said reflector having an opening through which 115 said lamp will pass.

In testimony whereof I affix my signature. 120

CHARLES F. BURGESS.
